(57) **CLAIM**

The ornamental design for a lamp holder with a front-mounted ground fault circuit interrupter receptacle, as shown and described.

DESCRIPTION

FIG. 1 is a top perspective view of a lamp holder with a front-mounted ground fault circuit interrupter receptacle, showing our new design;

FIG. 2 is a front elevation view thereof;

FIG. 3 is a top plan view thereof;

FIG. 4 is a back elevation view thereof;

FIG. 5 is a left-side elevation view thereof, a right-side view being a mirror image of thereof; and,

FIG. 6 is a bottom plan view thereof.

The broken line showing of the environment is for illustrative purpose only and forms no part of the claimed design.
